UNITED STATES PATENT OFFICE.

EDUARDO VITRONE, DECEASED, LATE OF CHICAGO, ILLINOIS; BY MARIA VITRONE, ADMINISTRATRIX, OF CHICAGO, ILLINOIS.

WINDOW-WASHING APPARATUS.

Application filed July 2, 1923. Serial No. 649,391.

To all whom it may concern:

Be it known that I, EDUARDO VITRONE, deceased, late a subject of the King of Italy, and a resident of Chicago, in the 5 county of Cook and State of Illinois, MARIA VITRONE, administratrix, of Chicago, aforesaid, have invented certain new and useful Improvements in Window-Washing Apparatus, of which the following is a specification.

This invention relates to an apparatus for scrubbing, washing and cleaning the outsides of vertically sliding window sashes of office and like buildings and has for its 15 object:—

To provide a simple and efficient structural formation and association of parts and mechanisms whereby the washing or cleaning operations are mechanically effected 20 by the operator from an inside position, and not necessitating at any time his presence at the outside of the window with consequent liability to accident, all as will hereinafter more fully appear.

25 In the accompanying drawings:

Fig. 1, is an outside elevation of a window with the improved implement in place.

Fig. 2, is a side elevation of the implement detached from the window.

30 Fig. 3, is a plan view of the same.

Figs. 4 and 5, are detail elevations illustrating different positions of the guide or track rollers of the implement.

Fig. 6, is an enlarged detail sectional elevation illustrating the implement in associated relation with the window sashes to be washed and cleaned.

Fig. 7, is an enlarged detail section, longitudinally of the washing roll or drum, 40 on line 7—7, Fig. 6, of the detachable journal connection between the main standard of the implement and the revolute washing roll of the same.

Fig. 8, is a detail transverse section of the 45 washing roll.

Fig. 9, is a detail perspective view of the attaching socket member by which the implement is held in place during actual use.

Like reference numerals indicate like 50 parts in the several views.

Referring to the drawings, 1 designates the window sill of a building, and 2 and 3 the respective upper and lower vertically sliding window sashes of the same.

55 4 designates a socket plate adapted for

fixed attachment to the sill 1 and formed with a horizontal socket or recess 5 in which a horizontal foot or plate is secured in place by a clamping screw 6 or like fastening means.

60 7 designates the pivot base of the implement, or a platform adapted for endwise insertion from either end into the socket or recess of the socket plate 4, and provided with centrally located pivot ears 8 for the standard or post now to be described.

9 designates the standard or post of the implement, pivoted at its lower end between the pivot ears 8 aforesaid, and carrying at its upper end a yoke or frame 10, the respective arms of which are formed at their upper and outer ends with laterally extending arms 11, which have spaced relation to each other corresponding with the window sash. The respective outer ends of the arms 11 are formed with journal orifices for the journal pins of a pair of washing and cleaning rolls as follows:—

12 designates the washing rolls or drum, consisting of a cylindrical central core of 80 rigid material around which are secured a series of radially disposed strips 13 of felt or the like, and which are secured in place by strips of channel metal 14 as shown more particularly in Fig. 8. Said core is 85 provided at one end with a fixedly attached journal pin for engagement in a journal orifice in an end of a lateral arm 11 aforesaid, while the other end of said core is provided with a fixedly attached stud 15 90 upon which the driving sheave 16 of the roll or drum 12 is slidably mounted by means of a keyway and key 17 as shown in Fig. 7.

18 designates a central end stud on the 95 driving sheave 16 adapted for journal engagement in one end of a lateral arm 11 aforesaid.

19 designates a spring tending to yieldingly force the driving sheave 16 away 100 from the core aforesaid, and maintain the journal stud 18 in its journal orifice in a lateral arm 11 aforesaid.

With the described construction a ready detachment and subsequent replacement of 105 a washing roll or drum 12 can be effected by a movement by hand of the driving sheave 16 toward said roll or drum 12 against the stress of the spring 19 so as to remove the journal pin 18 from engagement 110

in the journal orifice of a lateral arm 11 aforesaid.

20 designates the cleaning roll or drum of the improved implement, of substantially similar construction and detachable arrangement as the washing roll or drum 12 above described, and differing therefrom in that its series of radially disposed strips are formed of india rubber or like material 10 adapted to operate on the principle of the ordinary squeegee.

21 designates the driving sheave of the cleaning roll or drum 20, preferably of a counterpart construction and arrangement 15 to that of the sheave 16 of the washing roll or drum 12 above described.

22 designates an electric motor mounted centrally at the upper end of the standard or post 9, with its power shaft provided with 20 sheaves 23, 24, operatively connected to the aforesaid sheaves 16, 21 by endless belts, one of which is crossed, and so that both the washing roll 12 and the cleaning roll 20 will receive rotation in the same direction.

25 25 designates a spring secured to the window frame and adapted to yieldingly draw the upper end of the carrying standard 9, and the mechanisms carried thereby, toward the window sash during the actual use of 30 the implement.

26 designates supporting rollers or wheels attached to the lateral arms 11 aforesaid, by pivoted bars 27 and attaching bolts, so as to be capable of movement to a position in 35 which the washing and the cleaning rolls 12 and 20 will be held against stops or lugs on the arms 11, at a power distance from the surface operated on with a view to efficient work on the part of said rolls. This 40 provision is of especial value when the present implement is used for scrubbing or washing floors and the like.

28 designates the electric switch by which the operation of the motor 22 is controlled, 45 and said switch is preferably mounted near the lower end of the standard 9 for convenient access and manipulation.

In the practical operation of the implement in washing and cleaning windows, the 50 implement will be secured in position by an

engagement of an end of its base plate 7 in the socket plate 4, with the washing roll or drum 12 in contact with the outer surface of the glass of the window sash, and yieldingly held to bearing contact by the spring 55 25 aforesaid. The felt blades 13 of said roll or drum 12, having been previously charged with water, the motor 22 is now started, and said blades receives constant revolution, so that as the operator manually lowers the upper sash 2, for instance, in a gradual manner, a very effective washing of the outer surface of the glass will be attained.

With the completion of the above described washing operation, the implement is 65 reversed in its position in the socket plate 4, so as to bring the cleaning roll or drum 20 into operative contact with the glass of the window sash, to effect in a manner similar to that above described, a final cleaning 70 or wiping action on the outer surface of, the glass of said window sash.

Having thus finally described my said invention, what I claim as new and desire to secure by Letters Patent is:—

1. A window washing apparatus adapted for use on windows having vertically moving sashes, comprising a fixed base, a main standard secured to the fixed base, a yoke carried by the main standard, a cleaning roll having a cylindrical core, a driving sheave rotatably mounted on said yoke and separably and non-rotatably connected to the core, a motor on the main standard, and means operatively connecting the motor with 80 the driving sheave.

2. The combination of a socket plate formed with a horizontal socket, a platform provided with pivot-ears and adapted for endwise insertion in the socket plate, a main standard pivoted to the pivot-ears, a yoke carried by the main standard, a cleaning roll journaled in the yoke, and means for operating the roll.

Signed at Chicago, Illinois, this 30th day 95 of June, A. D. 1923.

MARIA VITRONE,
Administratrix of the estate of Eduardo
Vitrono, deceased.
